(57) CLAIM

The ornamental design for a compression garment, as shown and described.

DESCRIPTION

FIG. 1 is a front perspective view of a compression garment, showing my new design;

FIG. 2 is a rear perspective view thereof;

FIG. 3 is a front perspective view of a compression garment, showing a second embodiment of my new design;

FIG. 4 is a rear perspective view thereof;

FIG. 5 is a front perspective view of a compression garment, showing a third embodiment of my new design;

FIG. 6 is a rear perspective view thereof;

FIG. 7 is a front perspective view of a compression garment, showing a fourth embodiment of my new design;

FIG. 8 is a rear perspective view thereof;

FIG. 9 is a front perspective view of a compression garment, showing fifth embodiment of my new design;

FIG. 10 is a rear perspective view thereof;

FIG. 11 is a front perspective view of a compression garment, showing a sixth embodiment of my new design;

FIG. 12 is a rear perspective view thereof;

FIG. 13 is a front perspective view of a compression garment, showing a seventh embodiment of my new design; and,

FIG. 14 is a rear perspective view thereof.

The broken lines in the figures depict portions of the compression garment that form no part of the claimed design.

1 Claim, 14 Drawing Sheets
